UNITED STATES PATENT OFFICE

EDGAR E. GREVE, OF BELLEVUE, PENNSYLVANIA, ASSIGNOR, BY MESNE ASSIGNMENTS, TO OIL WELL SUPPLY COMPANY, OF PITTSBURGH, PENNSYLVANIA, A CORPORATION OF NEW JERSEY

AUTOMATIC RELEASING TONG

Application filed September 2, 1927. Serial No. 217,097.

This invention relates to improvements in tongs, and more particularly to automatic releasing tongs especially designed for use in screwing together sections of pipe or tubes entering into the construction of the drill stem or of rotary drilling apparatus employed for drilling oil, gas and other wells.

In rotary drilling systems of the character above mentioned, the drill stem or drill tool employed includes a number of pipe sections suitably joined together by threaded connections or threaded tool joints. In making up the stem or in adding new sections as the drilling progresses, it is the practice to hold the inserted stem stationary by suitable means cooperating with a temporarily fixed part of the rotary drilling machine, and revolve the section and its threaded connection to be added by applying a pipe tong to the 10 said section and rotating the tong and section by means of a rotating part of the rotary to which the tong is also connected.

In following the above stated practice in making up the stem or in screwing the 25 threaded pipe sections together, serious troubles have been encountered due to the continued rotation of the rotary and the tong after the connection is made sufficiently tight or made up, resulting in stripping the threads 30 or in some other manner injuring other parts of the mechanism.

Among the objects of the present invention are, to provide a tong construction having 35 means for automatically releasing the tong from operative engagement with the pipe when a predetermined resistance is encountered or at the time the joint is properly made up; to provide a tong construction embodying 40 automatically operable tong releasing means including a cam device, said means being operable to effect an automatic release of the tong when a predetermined resistance is encountered and while the tong is rotated in a single direction; and to provide a tong of the 45 character specified of strong and efficient construction capable of being readily placed in operative position on the pipe to be threaded.

Other objects and advantages of the present invention will be pointed out or become 50 apparent from the following description

taken in connection with the accompanying drawings.

In the accompanying drawings, which illustrate an application of my invention:

Fig. 1 is a top plan view of a tong embodying my invention, showing the tong in 55 pipe-engaging position;

Fig. 2, a side elevational view of the tong and a portion of a section of pipe;

Fig. 3, a horizontal sectional view taken on line III—III of Fig. 2, showing the tong in 60 released position; and

Fig. 4, a detail perspective view showing the cam constituting a part of the automatic releasing means.

As illustrated and as preferred, the tong embodying the present invention includes a handle member designated generally by the numeral 2, said member including a head portion 3 and two spaced-apart or cheek 70 members 4.

Adapted to be pivotally secured to the handle member, is a jaw member 5. Member 5 is formed with spaced-apart apertured lugs 6, said lugs being entered between the 75 cheeks 4 and pivotally secured thereto by a pivot pin 7, the latter being passed through the lugs and having its ends supported in the members 4. Jaw member 5 is formed with a relatively deep curved inner face 8 having 80 biting means to engage a pipe section A, as shown it is provided with a plurality of teeth 9, said teeth being rectangular in cross section and set into recesses formed in the said face 8 in such a manner as to present 85 a sharp edge for gripping the pipe. In addition to the elements mentioned, member 5 is preferably provided with a handle 10 designed to aid the operator in positioning the 90 tong on the pipe.

11 designates the second jaw member of the tong structure. This jaw, like jaw member 5, is pivotally secured to the handle member 2 and, as illustrated, includes a hollow body portion 12 and an outwardly projecting apertured portion or member 13 by means of which the jaw is pivotally secured to the handle member 2 by the same pivot pin 7 that connects the jaw 5 to member 2. Jaw member 11, as shown, is provided with one 100

or more pipe gripping teeth 14, of my preferred construction.

Located within the opening or chamber 15 of the hollow body portion 12, and arranged 5 for cooperation therein, is a piston-like member 16 and a relatively stiff spring 18, said spring being interposed between an end wall of the member 16 and an end wall of the chamber 15. In order to prevent wabbling 10 of the spring within the opening, the opening may be contracted as shown at 17.

Member 16 is designed to cooperate with a cam device, hereinafter described, and for this purpose it is provided with projecting 15 lugs 19 formed with openings to receive a roller carrying pin 20, having a contacting roller 21 mounted thereon. 22 designates a hand grip formed on the jaw member 11.

Positioned in advance of the piston-like 20 member 16 and its contacting roller 21, and designed to cooperate with member 16 for effecting a movement of the said member to vary the position of jaw member 11 relatively to the pipe to which the tong is applied, 25 I provide an irregularly shaped cam 23 having a drive fit on a pin 24 extending transversely of the head 3 of handle member 2, and having its bearings in end members 25, the latter being preferably welded to the 30 head, after machining the parts.

The shape of the cam member 23 is particularly shown by Fig. 4, and by a reference to this figure, it will be noted that the roller contacting face 27 is formed with a gradually 35 increasing pitch terminating at a point 28. When the roller 21 of the spring pressed jaw during its travel on the cam reaches this point, the compression of the spring 18 is greatest and will exert a maximum force in 40 gripping the pipe. From the point 28, the cam bevels off through ninety degrees, as shown at 29. This configuration permits the cam to be turned, by the travel of the roller 21 therealong, the cam turning on its rounded surface or face 30. It will be understood 45 that the movements just described will release the compression on the spring thereby automatically releasing the jaws of the tong from the pipe. The scale of the spring is 50 such that only sufficient rotative force may be applied to the pipe sections to screw the threaded ends home or to complete the threading operation and, therefore, when this operation is completed the tong will be released 55 from the pipe.

Pin 24 of the cam is provided with an operating handle 31 for returning the cam to its first position after the tong has been released from the pipe.

To prevent the tongs from swinging around and injuring the operator after release takes place, I provide a projecting member 32 integral with one cheek 4 of head 3, 60 said projection having a curved surface 33

for making contact with the pipe and preventing the tongs from flying free after being released.

Tongs of the character of my invention are 70 designed for use in connection with rotary drilling machines and in operation, after the tong has been placed about the pipe and in the position shown by Fig. 1, which may be readily accomplished by grasping the handles 10 and 22, the handle 2 is moved into contact with a post or other member, not shown, carried on a clockwise rotating part of the rotary. In the position shown by Fig. 1, with the roller 21 in contact with the cam, spring 18 exerts the desired and sufficient pressure to 80 maintain jaw 11 in operative gripping engagement with the pipe to rotate the same until a predetermined resistance is encountered or up to the time the threading operation is completed. When a resistance greater than is required to complete the threading operation is encountered, a continued movement of the handle 2 by the rotary will cause the roller 21 to pass the high point 28 of the cam 23, thus permitting the recoil of the spring to turn the cam through ninety degrees, thereby releasing the pressure and providing an automatic release of the tong from the pipe without arresting the rotative movement of the tong.

What I claim is:

1. A self-releasing pipe tong including a handle, a jaw-member pivotally mounted on the handle, a second spring actuated jaw-member also pivotally mounted on the handle and having a spring receiving chamber, a spring and a movable member in said chamber, and a cam carried by the handle and cooperating with the movable member and spring.

2. An automatic releasing tong having a plurality of cooperating jaw members, means for effecting a maximum gripping force while the tong is in operative position and a release of the tong when a predetermined resistance is encountered comprising a cam and spring-pressed means interposed between the cam and one of the jaw members.

3. An automatic releasing tong having a 115 plurality of cooperating jaw members, a handle on which the jaw members are pivotally mounted, means for effecting a maximum gripping force while the tong is in operative position and a release of the tong when a predetermined resistance is encountered comprising a cam carried by the handle, and spring-pressed means carried by one jaw member and disposed in operative engagement with the cam.

4. An automatic releasing tong having a 125 plurality of cooperating jaw members, a handle on which the jaw members are pivotally mounted, means for effecting a maximum gripping force while the tong is in operative position and a release of the tong when a 130

predetermined resistance is encountered comprising a cam carried by the handle, and spring-pressed means carried by one jaw member and disposed in operative engagement with the cam, said cam being rotatably mounted in the handle.

5. An automatic releasing tong having two co-operating jaw members, resilient means for transmitting to one jaw member a gripping force while the tong is in operative position, and cam means co-operating with the resilient means to exert said force and to automatically release the tong when a predetermined resistance is encountered and while

15 the tong is rotated in a single direction.

6. An automatic releasing tong including a handle member, two jaw members pivotally secured to the handle member, resilient means for transmitting to one of the jaw members 20 a gripping force while the tong is in operative position, and a cam co-acting with the resilient means and operable automatically to release the jaw.

7. An automatic releasing tong including 25 two pivotally mounted jaw members, resilient means for transmitting to one jaw member a gripping force while the tong is in operative position, and a cam device co-acting with the resilient means and operable automatically to release the tong when a predetermined resistance is encountered.

8. An automatic releasing tong including 30 jaw members movable relative to each other, an actuating member, resilient means for transmitting from said actuating member to one jaw member a gripping force while the tong is in operative position, and a cam device co-acting with the resilient means and operable automatically to release the tong when a

40 predetermined resistance is encountered.

9. A make-up tong comprising an actuating member, jaws for gripping and releasing the work, and a cam device for transmitting gripping pressure to a jaw from the 45 actuating member, said cam device permitting release of said jaw when, by movement of the actuating member relative to the jaw, the high point of the cam is exceeded.

10. A make-up tong comprising an actuating member, jaws for gripping and releasing the work, said actuating member being swingable relative to one of said jaws, and a cam device for transmitting gripping pressure to said jaw from the actuating member, said 55 cam device comprising an element movable along a cam by the swinging movement of the actuating member and permitting release of said jaw when said element passes over the high point of the cam.

60 11. A make-up tong comprising a handle, jaws movable relative to the handle for gripping and releasing the work, and a cam device for transmitting gripping pressure to a jaw from the handle, said cam device including a spring-pressed element movable along

a cam upon movement of the handle relative to said jaw and permitting release of said jaw when said element passes over the high point of the cam.

65 In testimony whereof I affix my signature. 70
